FRED M. SLATER, OF EASTON, PENNSYLVANIA, ASSIGNEE TO INGERSOLL-RAND COMPANY, OF JERSEY CITY, NEW JERSEY, A CORPORATION OF NEW JERSEY.

FRONT-HEAD CONSTRUCTION FOR PERCUSSIVE TOOLS

1,278,238.

Specification of Letters Patent. Patented Sept. 10, 1918.

Application filed December 10, 1917. Serial No. 208,506.

To all whom it may concern:

Be it known that I, FRED M. SLATER, a citizen of the United States, residing at Easton, in the county of Northampton and State of Pennsylvania, have invented a certain new and useful Improvement in Front-Head Construction for Percussive Tools, of which the following is a specification.

This invention relates to pneumatic or percussive tools and especially to an improved form of front head construction for such tools.

The objects of the present invention are to improve the present form of front head construction, to increase its resiliency, to make the construction more durable, and to completely inclose the resilient means within the parts of the front head.

In the usual form of front head construction at present used in percussive tools, the tool is provided with side rods extending the full length of the tool and having springs mounted on their front ends so that the front head may be resiliently held in its position against the front end of the cylinder. In this construction the resilient means which take the form of strong spiral springs are limited to two in number and with the increasing weight and power of percussive tools a sufficient resiliency can not be obtained conveniently without the use of very heavy wire, which is difficult to form into a suitable spring within the distance and dimensions available. It is therefore desirable to increase the number of individual springs in order that each one may be made of more suitable wire and have greater flexibility. It is also desirable that the springs be inclosed within the front head, for the reason that when mounted on the side rods they are exposed to injury when the tool is used and unduly increase the length of the side rods. It is to overcome the above disadvantages that the present construction has been devised.

Obviously, if desired, the improved construction may be applied to the back head of the percussive tool in the same manner as to the front head and in this construction the same advantages and improvements over the usual construction are obtained.

In the drawings annexed and forming a part of this specification,

Figure 1 shows a longitudinal view in section of the front end of a percussive tool

made in accordance with the present invention;

Fig. 2 an outside view of the same; and

Fig. 3, a front view of the tool.

Referring more particularly to the drawings, the cylinder or body of the percussive tool is shown at 1. At the front end of this cylinder 1 is located a front head 2 which is provided with a central longitudinal hole through which the drill steel 4 projects into the cylinder 5, far enough to be struck by the piston 6 at the forward end of its stroke. In advance of the front head 2 and surrounding the forward projection 2a of the same is a retaining collar 7 which is provided with a series of depressions 8 in each of which is located a compressive spiral spring 9. The springs 9 are of greater length than the depressions 8 so that the springs 9 project slightly from the depressions 8 and press against the flange 10 of the front head 2.

The side rods 11 are provided as usual in these tools extending from the rear to the front end of the tool. These pass through lugs 12 provided on the forward end of the cylinder 1, through the flange 10 of the front head 2 and through the retaining collar 7. These rods 11 may be tightened and loosened by means of nuts mounted on the rear ends of the side rods in the usual manner, (not shown).

From the above description it will be seen that the cylinder 1 and the collar 7 are secured in fixed relation to one another by the side rods 11, and that the front head 2 is resiliently held against the front end of the cylinder 1 by the springs 9 interposed between said front head and collar, thus permitting the front head 2 to yield when struck by the piston 6 and to recover its position against the front end of the cylinder 1, which occurs if the tool is operated when the drill steel 4 is not in proper position.

It is to be understood that the present showing and description disclose only one specific embodiment of my present invention and other forms and modifications are included within the spirit and scope thereof, as expressed in the appended claims.

What I claim is:

1. In a tool of the character described, in combination, a cylinder body, a cylinder head, and retaining collar, said retaining collar being provided with depressions,

springs contained within said depressions and resiliently engaging said cylinder head, and means to hold said parts in position.

2. In a tool of the character described, in combination, a cylinder body, a cylinder head, and a retaining collar, said retaining collar having a plurality of depressions, springs contained within said depressions and resiliently engaging said cylinder head and side rods engaging the cylinder body and retaining collar to hold said parts in position.

3. In a tool of the character described, in combination, a cylinder body, a cylinder head, and a retaining collar, springs interposed between said cylinder head and retaining collar and engaging said parts and means holding said parts together.

4. In a tool of the character described, in combination, a cylinder body, a cylinder head and a retaining collar, a plurality of

springs inclosed within said cylinder head and retaining collar resiliently forcing said cylinder head against said cylinder and means holding said parts together.

5. In a tool of the character described, in combination, a cylinder body, a cylinder head and a retaining collar, resilient means interposed between said cylinder head and retaining collar and engaging said parts and means holding said parts together.

6. In a tool of the character described, in combination, a cylinder body, a cylinder head, and a collar, a plurality of springs interposed between said cylinder head and collar and resiliently forcing one of said parts against said cylinder and means for holding said parts together.

In testimony whereof, I have hereunto set my hand.

FRED M. SLATER.
